Design No. 4,893, dated May 9, 1871.

DESIGN FOR A CARPET-PATTERN.

The Schedule referred to in these Letters Patent and making part of the same.

To all whom it may concern:

Be it known that I, CHARLES T. MEYER, of Newark, county of Essex, State of New Jersey, have originated and designed a new Pattern for Floor Oil-Cloths, Carpets, or other fabrics, of which the following is a full, clear, and exact description, reference being had to the accompanying drawings making part of this specification, and marked or designated No. 341, (three hundred and forty-one,) which fully represent said design, and are sufficient, without further aid, to enable any person skilled in the art to re-

peat it for practical use. The colors employed for different portions of this design may be varied to suit the convenience or taste of the manufacturer.

What I claim as my invention, and desire to secure by Letters Patent, is—

The design or pattern for floor oil-cloths, carpet or other fabrics, shown and described.

CHAS. T. MEYER.
